UNITED STATES PATENT OFFICE.

ALBERT L. DEAN AND PAUL W. BUCHANAN, OF LONGMONT, COLORADO.

TOBACCO-CAN.

1,187,612.

Specification of Letters Patent. Patented June 20, 1916.

Application filed January 25, 1915. Serial No. 4,414.

To all whom it may concern:

Be it known that we, ALBERT L. DEAN and PAUL W. BUCHANAN, citizens of the United States, residing at Longmont, in the county of Boulder and State of Colorado, have invented a new and useful Tobacco-Can, of which the following is a specification.

Our invention relates to improvements in tobacco cans to be used especially in packing tobacco for retail sale, and the objects of the invention are to provide a simple, cheaply constructed can from which material closely packed in the can may be easily and conveniently removed even when the can becomes partially empty. It is designed especially to obviate the necessity of loosening tightly packed tobacco in the bottom of a can by the use of some object such as a knife or pencil after the can is partially empty. We attain these objects by our tobacco can made with a movable and adjustable bottom, as illustrated in the accompanying drawings, in which—

Figure 1 is a side elevation of a can with the top in place and the movable bottom inside the can indicated by dotted lines. Fig. 2 is a top view or plan of the can shown in Fig. 1 with the top and bottom removed. Fig. 3 is a cross section of a can and bottom on line 3—3 of Fig. 1. Fig. 4 is a side elevation of one form of movable can bottom. Fig. 5 is a plan of the bottom shown in Fig. 4. Fig. 6 is a top view or plan of a modified form of can with top and bottom removed. Fig. 7 is one form of bottom, shown in plan, and shaped to fit in the form of can shown in Fig. 6.

The drawings represent a can adapted especially to be carried in the pocket. Such a can is preferably flattened or elongated in cross section, either with flat sides as shown in Fig. 2 or curved sides as shown in Fig. 6 to make it convenient to be carried in the pocket.

In the drawings the same letters of reference refer to like parts throughout the several views.

A is the body of the can and may be made of sheet metal, as tinned iron, bent in shape with its ends joined at a seam B. Seam B may be a folded or soldered seam or both, depending upon the size and strength of can desired. The lower edge of the body A at the sides of the open base of the can is rolled at C both outside and inside to strengthen the base of the can and to form an inward

flange as a suitable stop for the movable bottom.

D is an outward fold rolled in the body of the can near the top to strengthen the top 60 of the can and act as a suitable stop for the can cover.

E is the top or cover of the can and may be hinged to the can or not as desired.

F is a flat bottom shaped the same as the 65 plan of the can in which it is to be used. In the form of bottom shown in Figs. 4 and 5, the flat bottom has a peripheral flange G extending perpendicular to the flat bottom and wrapped around and joined to F about its 70 edges and folded or soldered at the joint H. Parts F and G may be folded together or soldered as may be desired and depending somewhat upon the size of can and weight of metal used. F and G, which together 75 form the movable bottom of the can, are made of size to fit snugly inside the body of the can A. If necessary the flat portion of the bottom F is notched at I and the flange G is creased at J to allow passage 80 along the seam B of the can.

To insure an even forward movement of the movable bottom, the peripheral flange, which acts as a guide, is made of width or height approximately equal to the width of 85 the can in which it is to be used. This is to prevent the possibility of the bottom twisting or turning in the can. The movable bottom is made of sufficient width to slightly 90 spring the sides of the can outward to insure a restraining pressure against the bottom by the sides.

One side of the body A is corrugated or creased as by rolling inward folds K in the side of the can. These corrugation folds are 95 provided to wedge against the flange of the movable bottom as the bottom is moved upward in the can and normally hold the movable bottom in any position in which it may be placed in the can. When the flat portion 100 of the movable bottom is pressed upward past any fold K the side of the can springs back under the bottom further insuring the bottom against falling back to the base of the can.

F' and G' in Fig. 7 and F'' and G'' in Figs. 1 and 3 show a simplified form of movable bottom. The flat portion F' and F'', respectively, being rolled as one piece with the flange G' or G''. This construction may be used in small cans where light weight metal is used. The bottom shown

in Fig. 7 at F' with its rolled flange G' is shaped to fit the particular form of box in which it is to be used and is creased at J' to allow passage along the seam of the can.

In packing this can for retail sale of tobacco the movable bottom is slipped in the can at the top and forced past the corrugations and against the roll C at the base. The can is then packed with tobacco, using

10 paper around the tobacco if desired, and the top put in place and sealed with the usual revenue seal.

15 The use of the can will be apparent. When tobacco is being used from the can the bottom is pressed upward inside the can by the fingers or thumb carrying the unused tobacco upward to the top of the can. In this manner the tobacco is always kept at the top of the can where it can be 20 readily removed with the fingers. The movable bottom fits snugly against the sides of the can and in addition the folds K wedge against the flange of the bottom and tend to hold it in place, and prevent its falling 25 back to the base of the can.

We claim:

1. A tobacco can having flattened sides

forming a can of elongated cross section, a movable bottom having a guide flange thereon and adapted to fit in said can snugly 30 against the sides thereof, inward folds in one of said flattened sides adapted to press against said flange and extend under the edge of said bottom when said bottom is forced upward in said can, substantially as 35 described.

2. A tobacco can having flattened sides forming a can of elongated cross section, a similarly elongated movable bottom having a peripheral guide flange of width approximately equal to the shorter width of said can and adapted to fit snugly inside said can, an inward flange at the base of said can forming a stop for said bottom, inward folds in one of said flattened sides adapted 40 to press against said flanged bottom and spring under the edge thereof when said bottom is forced upward in said can, substantially as described.
